UNITED STATES PATENT OFFICE.

MARTIN K. HENCH, OF CAMDEN, NEW JERSEY.

FORGING-MACHINE.

1,290,741.

Specification of Letters Patent.

Patented Jan. 7, 1919.

Application filed March 31, 1917. Serial No. 158,796.

To all whom it may concern:

Be it known that I, MARTIN K. HENCH, a citizen of the United States of America, and resident of the city and county of Camden, State of New Jersey, have invented a certain new and useful Improvement in Forging-Machines, of which the following is a true and exact description, reference being had to the accompanying drawings, 10 which form a part thereof.

The general object of my present invention is to provide an improved forging mechanism especially adapted for use in forging angle-pieces out of structural bars, 15 and particularly out of ordinary angle bars.

The various features of novelty which characterize my invention are pointed out with particularity in the claims annexed to and forming part of this specification. For 20 a better understanding of the invention, however, and of the advantages possessed by it and specific objects attained by its use, reference should be had to the accompanying drawings and descriptive matter in 25 which I have illustrated and described preferred embodiments of my invention.

Of the drawings:

Figure 1 is a side elevation of my improved angle bending machine with an upper portion of the same broken away;

Fig. 2 is a plan view of the machine shown in Fig. 1 with an upper portion of the same removed;

Fig. 3 is an elevation at right angles to 35 Fig. 1;

Fig. 4 is a side elevation of a portion of the apparatus taken on a larger scale than Figs. 1 to 3, showing a part of the external die and a work holder connected thereto, 40 and showing in section a piece of work held thereby;

Fig. 5 is a sectional view taken on the line 5—5 of Fig. 4;

Fig. 6 is a plan view of the active forging elements in an initial stage of angle bending operation;

Fig. 7 is a view taken at right angles to Fig. 6;

Fig. 8 is a view taken similar to Fig. 6 50 showing the condition of the apparatus at the conclusion of the angle bending operation;

Fig. 9 is a view taken at right angles to Fig. 8;

Fig. 10 is a view taken similarly to Fig. 6 illustrating the use of formers of different

shape from those employed in Figs. 1 to 9 inclusive; and

Fig. 11 is a view taken similar to Fig. 6 illustrating a further modification. 60

My improved forging machine, in the form illustrated in the drawings, comprises a massive base A, provided with a horizontal bed A', grooved to adjustably receive a die supporting abutment B. As shown, 65 the abutment B carries or supports an internal angle forming die B' having a removable tip portion B² dovetailed into the body of the die. Coöperating with the stationary die or former is a horizontally 70 movable die or former made in three sections D, C and D¹⁰, which are shaped to co-operate with the die B' in forging angles. The middle section C is formed with a notch 75 at its front end conforming in shape to the adjacent portion of the wedge-shaped internal former B. The side sections D and D¹⁰ have inclined faces d which, in the condition of the apparatus shown in Fig. 8, form extensions of the adjacent walls c of 80 the notch of the die section C. Each of the external die sections C, D and D¹⁰ is provided with an individual advancing plunger C', D' and D¹¹ respectively, working in cylinder spaces C², D² and D¹² respectively, 85 (see Fig. 2). The admission to, and exhaust from the cylinders C², D² and D¹² of the working fluid is controlled by hand operated valves C³, D³ and D¹³ respectively. Small plungers C⁵, D⁵ and D¹⁵ working in 90 cylinders provided for the purpose in the framework A and connected at all times to a source of fluid under pressure, serve to retract the former sections C, D and D¹⁰ when the exhaust of the pressure fluid from the 95 cylinders C², D² and D¹² permits this. As shown, a transverse bar C D is recessed in and bolted to the die sections D, C and D¹⁰ and thus detachably but rigidly unites these die sections into a single die element. 100

Each of the side formers D and D¹⁰ is cut away as indicated at D⁸ to provide a clearance space for a work holder element D', pivotally secured in the recess D⁸ by a corresponding bolt D⁶. Each of the work 105 holders D' comprises a horizontal body portion received in the corresponding recess D⁸, and a vertical pin portion which is spaced away from the front wall of the corresponding side former far enough to receive the 110 vertical flange X' of an angle bar X having its horizontal flange resting on the upper

- ends of the pin portion of the work holders D'. Each work holder D' is so pivoted with respect to the former angle d² at the junction of the inclined face d of the former with the transverse end face d', that as the angle forming operation proceeds the work holders D' may swing from the positions shown in Fig. 5 through the positions shown in Fig. 6 into the positions occupied by them in Fig. 8. Advantageously, the corner d² of each of the side formers is rounded off to coincide with the surface of a cylinder which is coaxial with the corresponding bolt D⁶ and is tangential to the die surfaces d and d'.
 10 8. Mounted above the dies B', C, D and D¹⁰ and coöperating with these dies, as herein-after described, is a vertically acting air hammer E. The latter works in a cylinder E' which is supported by the machine super-
 15 20 structure which comprises a main upright portion A¹⁰ and posts A¹¹. Advantageously, this superstructure may support air compressing means for supplying the compressed air needed for the operation of the hammer E. Inasmuch as the character of the means for supplying the working fluid to the cylinder E' forms no part of my present invention I have not thought it necessary to illustrate this means herein. The admission of 30 the working fluid to, and its exhaust from the cylinder E' is controlled by a valve E².
 In the operation of forging an angle-piece out of an angle bar, the latter is first placed upon the two work supports D' with the 35 formers B, C, D and D¹⁰ occupying the positions shown in Fig. 2. The formers C, D and D¹⁰, and the hammer E, are then manipulated to bring the bar into the finished shape shown in Figs. 8 and 9.
 40 45 50 55 60 65 70 75 80 85 90 95 100 105 110 115 120 125 130
 In a preferred mode of operation with the die parts C, D and D¹⁰ rigidly secured together by the bar C D, these connected die parts are first advanced to slowly bend the bar into approximately the shape desired. Figs. 6 and 7 illustrate the position of the parts and the condition of bar X during an intermediate stage of the bending operation. During this bending operation the hammer E is manipulated to beat out the buckle X² formed in the upper flange of the bending operation and after the bar is bent into approximate shape the die parts C, D and D¹⁰ are manipulated to subject the blank to a series of hammer blows which are interspersed with hammer blows imparted to the top flange of the bar by the hammer E. By proceeding in the manner described material is provided at the apex of the angle to insure a proper contour and proper strength at the apex of the angle when the latter is finished.
 The apparatus illustrated and described forms a simple and effective mechanism for accomplishing the desired result. With its use it is possible to make angle pieces out

of straight bars of angle bar cross sections with the apices of the angles formed sharply and uniformly defined and of proper strength, without requiring any cutting of the blanks and without requiring highly skilled operatives. It will of course be understood that the shapes of the angles formed may be readily varied by replacing one set of dies or formers by another; for instance, the apparatus shown may be readily changed to make angles rounded at their apices by simply replacing the former parts B' and C of Figs. 1 to 9 by the parts B¹⁰ and C¹⁰ respectively of Fig. 10.

In Fig. 11 I have illustrated another form of forging operation which may be carried out with the apparatus shown in Figs. 1 to 5 inclusive, when modified by the simple replacement of the die parts B', C, D and D¹⁰, by die parts B²⁰, C²⁰, D²⁰ and D²⁰⁰, respectively, and those skilled in the art will understand that many different special forging operations may be carried out with the mechanism disclosed by the aid of the die parts already referred to, or other more suitably shaped die parts. While, as I have already stated, I prefer to rigidly secure the movable die parts together for use in carrying out a simple angle forging operation, it is by no means essential that these parts should be secured together for this operation, and the capacity for individual operation of the different movable die parts made possible by the omission or removal of the part CD, as shown in Fig. 11, is a desirable one in performing many forging operations.

While in accordance with the provisions of the statutes I have illustrated and described the best forms of my apparatus now known to me, it will be apparent to those skilled in the art that changes can be made in the forms of the apparatus disclosed without departing from the spirit of my invention hereinafter claimed.

Having now described my invention what I claim as new and desire to secure by Letters Patent, is:—

1. An angle forging machine comprising in combination a stationary internal forging die, and a movable coacting external die of complementary form formed in three sections, one adapted to coact directly with the angle of the internal die and the others to coact with the flange forming portions of said die, means for guiding said die sections along parallel lines, and independent means for moving said sections toward and away from the stationary die.

2. An angle forging machine comprising in combination a stationary internal forging die, and a movable coacting external die of complementary form formed in three sections, one adapted to coact directly with the angle of the internal die and the others

to coat with the flange forming portions of said die, means for guiding said die sections along parallel lines, independent means for moving said sections toward and 5 away from the stationary die, and means for detachably securing said die sections together in assembled form so that they will move together.

3. A forging machine comprising in combination a supporting frame-work, an abutment adjustably mounted thereon, a stationary die supported by said abutment, a movable die, means mounted in said supporting frame-work for moving said movable 10 die horizontally toward and away from said stationary die, a second movable die, and means mounted in said frame-work above the stationary die for moving said second movable die vertically into and out of engagement with work engaged by the first 15 mentioned dies.

4. An angle forging machine comprising in combination relatively movable internal and external forging dies and work-holders 20 pivotally connected to said external die and each comprising a portion extending transversely to the line of relative movement of said dies and spaced away from and adapted to swing about an axis parallel to the 25 die faces.

5. In a forging machine the combination of relatively movable internal and external die members, said external die member being formed with a notch or depression in its side adjacent the stationary die, the ends 35 of the wall of which extend laterally beyond the sides of said external die, and a pair of work-holders pivotally connected to said external die adjacent the ends of the wall of said notch, and comprising portions extending transversely to the line of relative movements of said dies and spaced away from and adapted to swing about the ends of said wall.

6. In an angle forging machine the combination with a wedge shaped internal die, of a coöperating external die movable toward and away from the first mentioned die, and provided with a wedge shaped recess in its side adjacent said internal die, 50 which is of greater width than said internal die, and a pair of work-holders pivotally connected to said external die, one adjacent each outer end of the wall of said notch and comprising a portion extending parallel to 55 the wall of said notch and adapted to swing around the corresponding end of the wall of said notch.

MARTIN K. HENCH.
